[57] CLAIM

The ornamental design for a vehicle tire, as shown and described.

DESCRIPTION

FIG. 1 is a perspective view of a vehicle tire showing our new design, it being understood that the tread pattern is repeated throughout the circumference of the tire, the opposite side being substantially the same as that shown;

FIG. 2 is a side elevational view thereof;

FIG. 3 is an end elevational view thereof;

FIG. 4 is an enlarged fragmentary plan view thereof; and

FIG. 5 is an enlarged sectional view thereof taken along line 5—5 in FIG. 4.

FIG. 1

FIG. 2

FIG. 3

FIG. 4

FIG. 5
